UNITED STATES PATENT OFFICE.

JONATHAN HEACOCK, OF HIGHLANDS, NORTH CAROLINA.

REVERSIBLE PLOW.

1,265,652.

Specification of Letters Patent.

Patented May 7, 1918.

Application filed January 8, 1916. Serial No. 71,049.

To all whom it may concern:

Be it known that I, JONATHAN HEACOCK, a citizen of the United States, residing at Highlands, in the county of Macon and 5 State of North Carolina, have invented certain new and useful Improvements in Reversible Plows; and I do hereby declare the following to be a full, clear, and exact description of the invention, such as will enable others skilled in the art to which it 10 appertains to make and use the same.

This invention relates to plows, and the primary object of the invention is to provide a plow structure which includes a pivotally 15 supported plow stock or standard having plow supporting heels formed upon each end of the same.

Another object of this invention is to provide a plow as specified, which is comparatively simple in construction and operation, which includes means for holding the ends of the plow standard rigidly during the plowing operation of the same, and further to provide a novel form of clevis which is 25 attached to the forward end of the plow beam so that upon the reversing of the plow shovels or shares, the line of draft of the plow may be varied for the purpose of eliminating unnecessary side draft.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the 40 several views, and in which:—

Figure 1 is a side elevation of the improved plow,

Fig. 2 is a top plan view of the plow,

Fig. 3 is a perspective view of the plow 45 standard,

Fig. 4 is a perspective view of a part of the plow structure.

Referring more particularly to the drawings, 1 designates the beam of the plow, 50 which is provided with a longitudinally extending opening 2 formed therein. The intermediate portion of the beam 1, which is provided with the slot 2 is greater in width than the ends 3 and 4 of the same. The 55 rear end 4 of the beam 1 has handle carrying blocks 5 secured to its side by means of

a bolt 6. The blocks 5 are greater in thickness than the end 4 and are provided with cut-out portions 7 which receive the sides of the ends 4 of the beam 1. A shoulder 8 is 60 formed upon the blocks, which is angled to conform to the angle of the plow handles 9. The forward edges of the lower ends of the handles 9 rest against the inner edges of the shoulders 8, thereby eliminating liability 65 of swing or pivotal movement of the handles during operation, and providing means whereby the handles may be detachably attached to the plow beam by a single bolt.

The beam 1 has a pin 10 extending transversely across the same equidistant of the ends of the slot 2, which pin also extends through the center of the standard 11, which is pivotally mounted upon the pin 10.

The standard 11 which is adapted to carry 75 a plow share of ordinary construction is enlarged intermediate its ends to a width substantially equal to the width of the slot 2 and it is provided with an opening 12 formed therein for reducing the weight of 80 the standard. The ends 14 and 15 of the share are reduced with respect to the thickened portion 11, and they curve oppositely therefrom, as is clearly shown in Figs. 1 and 4 of the drawings. The ends of the stand- 85 ard 11 are provided with openings 16 and 17 which are adapted to receive the heel bolts of plow shares.

The end 4 of the beam 1 has a metallic plate 20 secured to one side of the same, 90 which is rolled to form a bearing 21. The bearing 21 rotatably supports the angled end of a rod 22. The rod 22 extends upwardly from the plow beam 1 and forwardly over the same. The upper end 23 95 of the rod 22 is screw threaded, and has a nut 24 adjustably mounted thereon, to which nut is attached a hook 25. The hook 25 is provided for engaging the upper end of the pivotally supported standard 11, for 100 holding the same rigidly in place during the plowing action of the plow.

A clevis 26 is attached to the forward reduced end 3 of the plow beam 1 and it has its forward edge curved, as is shown at 27, 105 for guiding the split ring usually employed for attaching a swingletree to a plow beam, from one of the corners 28 of the clevis to the other, when the plow standard is moved for changing from either a right to a left 110 plow blade or vice versa, so as to properly align the draft of the plow and eliminate

unnecessary side draft which would be occasioned in case the swingletree could not be moved from one side of the clevis to the other.

3 When it is desired to change the position of the standard 11, when the ends of the field are reached for changing from either a right hand breaking plow blade to a left hand breaking plow blade, or vice versa, the 10 upper end of the standard is moved toward the handles 9, which moves the same out of the hook portion 30 of the hook 25, and frees the same from connection with the hook. After the standard has been disconnected from the hook, the rod 22 is swung outwardly, out of the way of the path of the plow share or blade carried by the standard, and the standard is reversed.

From the foregoing description taken in 20 connection with the accompanying drawings the advantages of construction and of the method of operation of the improved reversible plow will be readily apparent to those skilled in the art to which this invention appertains and, while in the foregoing description, the principle of the operation of this invention has been described together with various features of construction, it is to be understood that certain minor features 26 of construction, combination and arrangement of parts may be altered to suit practical conditions provided such alterations are comprehended within the scope of what is claimed.

35 What is claimed is:—

1. In a plow structure, the combination,

of a plow beam having its intermediate portion enlarged, said intermediate portion being provided with a longitudinally extending slot, a pin extending transversely through said beam intermediate the ends of said slot, a standard pivotally mounted upon said pin, a rod carried by said beam, a nut adjustably mounted upon one end of said rod, a hook carried by said nut and adapted for engagement with one end of said standard for holding it rigidly in position, the ends of said standard being curved oppositely.

2. In a plow structure, the combination, 50 of a plow beam having its intermediate portion enlarged, said intermediate portion being provided with a longitudinally extending slot, a pin extending transversely through said beam intermediate the ends of said slot, a standard pivotally mounted upon said pin, a rod carried by said beam, a nut adjustably mounted upon one end of said rod, a hook carried by said nut and adapted for engagement with one end of 55 said standard for holding it rigidly in position, the ends of said standard being curved oppositely, a clevis connected to the front end of said beam, said clevis having its forward side curved for providing two 60 sockets upon each side of said beam.

In testimony whereof I affix my signature in presence of two witnesses.

JONATHAN HEACOCK.
